United States Patent Office

Des. 214,568
Patented July 1, 1969

214,568

DART BOARD

George T. Shannon, San Bruno, Calif., assignor to Michael G. Ellsworth

Filed May 17, 1968, Ser. No. 11,986

Term of patent 14 years

Int. Cl. D21—01

U.S. Cl. D34—5

The figure is a top plan view of the dart board of my design.

The dart board is flat and of conventional thickness.

I claim:

The ornamental design for a dart board, as shown and described.
